Frank W. Mix
By James Shepard Atty.

UNITED STATES PATENT OFFICE.

FRANK W. MIX, OF TERRYVILLE, CONNECTICUT.

PADLOCK.

SPECIFICATION forming part of Letters Patent No. 223,528, dated January 13, 1880.

Application filed June 9, 1879.

To all whom it may concern:

Be it known that I, FRANK W. MIX, of Terryville, in the county of Litchfield and State of Connecticut, have invented certain new and useful Improvements in Padlocks, of which the following is a specification.

My invention consists in the peculiar construction of certain parts, and in their combination with themselves and with other parts or devices, as hereinafter more fully described.

In the accompanying drawings, Figure 1 is a front elevation of a lock which embodies my invention. Fig. 2 is a like view with part of the case removed and the parts represented as locked. Fig. 3 is a like view of the same represented as unlocked. Fig. 4 is an inside view of the part of the case which is removed from Figs. 2 and 3. Fig. 5 is a transverse section of said lock on line *y y* of Fig. 2. Fig. 6 is a transverse section of the cam-cylinder on line *x x* of Fig. 3, showing the manner of coupling it to the key-cylinder; and Fig. 7 is an end view of the cam-cylinder.

A A' designate the two halves of the lock-case; B, the shackle, preferably provided with a spring, *e*, for throwing it open, as is common in padlocks. If desired, a sliding or other shackle might be substituted for the swinging shackle B without materially changing the other features of the invention.

I prefer to make the case practically a solid one, and I divide it into two halves, A A', on one side of the middle line, and for convenience of putting in some of the parts I form a flange or lip, *k*, on the half A, which shuts over the edge of the other half, A', as shown in Fig. 5. I also make a cap, E, at the lower end for closing that end of the case. The two halves A A' are put together, and then bored out longitudinally and recessed transversely to receive other parts, hereinafter described.

C designates a cylinder or key-hub fitted in the longitudinal bore of the case, slotted longitudinally to receive a flat key, and provided with a series or set of pin-tumblers, the ends of which enter the key-slot after a well-known manner in pin-locks. The case also, at one side of the key-cylinder, is provided with a set of spring-actuated pins for joint action with the pins in the key-cylinder and their recesses, as indicated by broken lines in Figs. 2 and 3, to lock the key-cylinder immovably in its place in a well-known manner by well-known means, so that it is considered unnec-

essary to describe the same except in general terms.

I have specified the key-cylinder as containing but one set or series of pins; but the sets may be duplicated as many times as may be desired; and any other form of pins—as, for instance, threaded or grooved instead of plain, and flat instead of round—may be substituted, if desired.

The key-cylinder C is reduced in size at its lower end to allow a collar or circular flange, *n*, of the cap E to enter the bore of the case. (See Figs. 2, 3, and 5.) The neck or lower end of the key-cylinder C bears a stop-pin, *a*, and a portion of the flange *n* is cut away, as shown in Fig. 5, far enough to allow the cylinder to make one-quarter of a revolution, while the solid portions of the flange act in connection with the stop-pin *a* to limit the motion of the cylinder to said quarter of a revolution.

At the upper end of the key-cylinder, and in the same longitudinal bore of the case, there is a cam-cylinder, D, bearing a cam, *b*, at its upper end. The middle portion of said cylinder is reduced to receive a proper spring, *f*, one end of which is connected to the case and the other end to said cylinder, so as to constantly bear upon it with a tendency to turn it into the proper position for locking the shackle. The lower end of this cam-cylinder is bored out axially to receive a neck formed axially on the end of the key-cylinder C. It is also recessed, as shown in Fig. 6, to receive a pin, *c*, extending upwardly from the key-cylinder, so that one cylinder may make part of a revolution independently of the other when the pin *c* engages the wall of the recess and necessitates their simultaneous movement. The recess and pin which constitute the slack coupling of these two cylinders are relatively arranged so that one cylinder may make just one-quarter of a revolution independently of the other.

The cam *b* on the cam-cylinder D engages and operates a sliding bolt, *d*, having a beveled end, which engages the nose of the shackle. In connection with the cam-cylinder there is a locking-pin, *g*, having a beveled shoulder, *m*, and a spring, *h*, Fig. 3, which spring has a tendency to throw said pin toward the cam-cylinder and into a notch (see Fig. 7) in said cylinder made to receive said locking-pin whenever said notch coincides with its end.

The stops which limit the movement of the

key-cylinder are so placed relatively to the pins which lock said cylinder in place that when the cylinder is in the proper position for being locked by the pins it is turned backward to its greatest extent, which position is represented in Fig. 5, and the coupling of the key-cylinder and cam-cylinder is so arranged that when the lock is locked, as shown in Fig. 2, a forward movement of the key-cylinder necessitates a like movement of the cam-cylinder.

To unlock the lock a key properly formed to control the pin-tumblers in such manner as to release the key-cylinder is inserted, when it is turned in the direction of the arrow in Fig. 6, thereby carrying said cylinder, together with the cam-cylinder, one-quarter of a revolution from the position shown in Fig. 2 into the position shown in Fig. 3. In doing so the cam *b* withdraws the sliding bolt out of the notch in the nose of the shackle, and also the notch in the edge of said cam-cylinder is brought in front of the end of the locking-pin *g*, when its spring *h* forces it into said notch and locks the cam-cylinder immovably in its place, and with the locking-bolt *d* unlocked, all as shown in Fig. 3. If desired to withdraw the key, the quarter play in the slack coupling before described allows the key-cylinder to be turned backward to its former position, the key removed, and the key-cylinder to be again locked immovably in the case, while the cam-cylinder, shackle, and connecting parts remain unmoved in their unlocked position.

In order to lock the shackle, it is only necessary to press it into the case, when its nose will engage the beveled shoulder *m* of the locking-pin *g* and withdraw it from the cam-cylinder, thereby releasing said cylinder and allowing its spring to return it to its former position, thus moving the cam *b* to throw the sliding bolt into engagement with the shackle, all as shown in Fig. 2. When the spring *f* thus acts upon the cam-cylinder to move it back after the key-cylinder has been locked, said movement takes up all the slack or play in the coupling, so that, upon reinserting the key to unlock the lock, the cam-cylinder will move with the key-cylinder, as before described.

In case a lock is desired from which the key cannot be removed when the shackle is unlocked, then the cam-cylinder may be formed solid on the end of the key-cylinder without any slack coupling, and the other parts will operate as before described.

In the lock as described, if the key-cylinder is not turned back by hand before the shackle is forced into the case, then the spring *f* will move both the key-cylinder and the cam-cylinder back to their proper position for locking, the same as though they were one cylinder. Thus it will be seen that the key-cylinder is so arranged as to be spring-actuated, if desired to so use it.

By making the case in two halves divided

one side of the middle line and bored out, as described, the cylinders may be operated when one-half is removed without any liability of accidental displacement.

I am aware that the model in the case of 70 Harrison's patent, January 8, 1856, No. 14,059, shows a padlock-case divided into two unequal parts, but without a rotary cylinder, as herein described for my lock.

I am also aware that a prior English patent shows a padlock with a pin-cylinder having both a longitudinal and partial rotary movement, which cylinder, when in a certain position, might be partially rotated by a spring acting immediately through the locking-bolt, but 80 which cylinder was also provided with a spring for throwing it longitudinally, so as to take it out of the position in which the spring first named could act upon it. Both of these prior devices are hereby disclaimed. 85

I claim as my invention—

1. In a padlock, the cylinder of a pin-tumbler lock and suitable connecting locking mechanism, in combination with a spring acting directly upon said cylinder to partially rotate it, 90 and so combined therewith that the cylinder is always under the influence of the spring in all the various changes in the position of the parts, substantially as described, and for the purpose specified. 95

2. In a padlock, the combination of the nose of the shackle, cam-cylinder *D*, spring *f*, cam *b*, and sliding bolt *d*, substantially as described, and for the purpose specified.

3. The combination of the cam-cylinder *D*, 100 spring *f*, cam *b*, sliding bolt *d*, spring-actuated locking-pin *g*, and nose of the shackle, substantially as described, and for the purpose specified.

4. In a padlock, the spring-actuated cam-cylinder, operating suitable mechanism for locking the shackle, in combination with the rotating key-cylinder and the slack-coupling, substantially as described, and for the purpose specified. 105

5. In a pin-tumbler lock, the combination of suitable locking mechanism, a rotating cylinder operated in one direction by a key, a spring acting to return said cylinder in the opposite direction, and suitable mechanism 115 for locking said cylinder against the action of said spring when the cylinder is acting upon the sliding bolt to hold it in an unlocked position, substantially as described.

6. The lock-case *A*, divided longitudinally, 120 in combination with the rotating key-cylinder of a pin-tumbler lock lying partially on each side of the dividing-line of said case, and with its axis parallel thereto, substantially as described, and for the purpose specified. 125
